UNITED STATES PATENT OFFICE.

GEORGE W. MULLER, OF WASHINGTON, DISTRICT OF COLUMBIA.

TRACK-BED CONSTRUCTION AND ARRANGEMENT.

Application filed December 1, 1928. Serial No. 151,902.

This invention relates to railway track and track bed construction and arrangement, and comprises a continuous support for track rails composed of ties made from any chosen material, plastic, wood, stone or metal having special formation and disposition for the purpose of increasing the load resisting qualities of the bed and rails in order to withstand the material present increase of the weight of rolling stock and the probable continued additions to the same in future.

Another object of this invention and a feature of the construction hereinbelow set forth is the making of the road-bed waterproof, by shedding the water to both sides of the track in order to prevent the water, snow or sleet from seeping through top, sides and under the foundation of the road-bed and softening up the supporting ground or earth of the embankment thereby permitting the ties to sink and destroy the desired track level, and calling for repeated repairs.

Another object of this invention is to provide a rail bed made up of a plurality of ties, sills or bases, placed side by side closely or touching each other and making a uniform, continuous supporting base for the track.

Another object of this invention is the production of a rail bed of the character stated composed of associated individual members which may be termed ties, sills or bases, of the special formation shown and described, and having the proper proportions as to thickness, length and width designed to withstand the great loads, pressures and impacts pounding thereon during heavy service.

Another object of this invention is the provision of a bed member of the fashion and material set forth herein and adapted to receive an under-rail support, or to be used without such support. Under certain circumstances the under-rail is of very great advantage in many ways, as it gives additional support to each member acting as a carrier beam longitudinally beneath the track rails.

Another object of this invention is the construction of a track rails support or tie having a recessed under surface whereby the ballast is held at the ends of the ties, and

forced by the pressure of the traffic into contact with the ties and prevented from displacement and spreading.

Another object of this invention is the formation of ties each having a narrower end and a wider end whereby they may be laid each tie reversed in position with respect to the adjoining tie to form a straight track bed, or placed in the same way to form curved portions of the roadway.

With the above and other objects following from them, this invention consists of certain original features of construction and arrangement as described in the following explanation of the structure and operation, and as illustrated in the accompanying drawings showing the preferred form.

Of the drawings Figure 1 represents a top plan view of two ties constructed in accordance with this invention, and arranged side by side in contact. The track rails are omitted.

Figure 2 is an end view of such associated ties, partly in section to disclose the curving recess formed in the bottom of each tie near its end.

Figure 3 is a bottom plan view of the two members or ties illustrated in Figure 1, and shows the formation of the underlying portions of the ties.

Figure 4 is a cross section of one of the ties on the broken line 4-4 of Figure 3, showing also in section the reinforcing elements embedded in the material of which the tie is made.

Figure 5 is a vertical transverse section of the roadbed and rail pillow members. This section is taken between the ties, and illustrates the under-rails in section.

Figure 6 is a section of the roadbed similar to Figure 5, but the section extends longitudinally through the tie and discloses the reinforcing elements therein. The rails, tie plates and pillow members are shown in section.

Figure 7 is a perspective view of the reinforcing elements placed lengthwise in each tie. One of the side wooden bars which augment the elasical stiffness and deadening means of the tie is omitted to clear the view.

Figure 8 represents the particular arrangement of the ties, sills or bases constructed in accordance with this invention when it is necessary that the track shall be laid in a

straight direction and also more or less curved or offset with respect to the original or normal line of the rails.

Figure 9 is a side view of the end of one of the ties, and shows an additional water shed at the side of the track whereby the water is led entirely away from the bed of the rails and caused to flow downwardly and outwardly at the side of the ballast or filling.

Throughout the description and drawings the same part is referred to by the same number.

Considering the drawings, the tie, base or sill member constituting the track rails support is referred to generally by the numeral 1. As illustrated in Figure 8, the members 1 each have a narrower end 2 and a wider end 3, and the sides of the members 20 are thus inclined to each other. By reason of this formation the track bed may be laid either for a straight track by reversing the positions of the members with respect to each other, or by placing them side by side 25 in the same relative positions the track may be extended in a curving direction. On its upper surface it has a middle flat portion 4 adapted to carry the track rails 5. The flat portion or track rails carrying portion occupies the middle of the length and width of the member 1, and on either side thereof sloping from a middle line both ways to the end of the member are the water shedding inclines 6, 7, 8, 9. It will be noted in Figures 35 1, 2, 4 and 5 that the water shedding inclines slope away from the flat portion 4 transversely as well as longitudinally. The purpose is to direct all the surface water off the ends of the members 1, and in Figure 9 an additional water shed 10 is illustrated. The form and position of this additional part is in no sense limited to the shape set out in the drawings. As best shown in Figures 1, 2 and 4, the water shedding inclines at the 45 sides of the flat portion 4 are bounded lengthwise by raised edges or beads 11. It will be observed further in the Figures 2 and 4 that the vertically disposed side portions of the member 1 designated by reference number 12 and leading downwardly from the beads 11 are formed outwardly curving with a swell or slight oval in order that the pressure will not break off the beads or standing portions.

Attention is directed particularly to Figures 2 and 4 wherein it will be seen that the continuations 13 of the side walls of the member 1 slant downwardly and inwardly on either side at the end portions of the member. This formation results in the side recesses 14, and it will be observed that the top portion or surfaces of the recesses 14 marked 15 slant upwardly and towards the middle of the member 1 the inner limits of the recesses being the transverse solid por-

tion 16 of which the lower side of each member is provided with two, spaced apart in correspondence with the width of the track, and usually joined by a longitudinal solid portion 17 as best shown in Figure 3. Between the side end recesses 14 at the ends of the member 1 are formed the dished depressions 18. The depressions or hollows 18 are best shown in Figures 2, 3 and 6. These depressions or concave bottoms 18 at each end of the member 1, beginning at the ends and back to the bearing portion where the member rests on the under-rails 19, have rounded corners on the bottom and rounded corners on the outside edges, so that when the tamping is done the ballast or fill can be forced easily underneath, and rolled back into the hollow or rounding portion in a hump, and when once tamped in place and the pressure of the traffic put on, the fill cannot come out, because of the concave part of the tie hugging over the ballast and the fill in the pockets or depressions described.

As stated above the solid transverse portions 16 of the member 1 are spaced apart as illustrated in Figure 3, and between them on either side of the longitudinal solid bar shaped joining portion 17, are two part recesses 20 and 21. Each of the recesses 20 and 21 is provided with a surface slanting upwardly and towards one of the transverse solid portions, so that when pressure is put on the top center the ballast or filling will be forced outward and upward and back against the transverse solid portions or shoulders 16.

Considering Figures 4, 6 and 7, the reinforcing elements of this invention will be understood. Such elements comprise side truss rods 22 and 23 connected at separated points by cross bars 24. The truss rods are enclosed in a tubular netted openwork wire or metal device 25, which has an upper flat portion 26, a lower flat portion 27, and outwardly pointed angular side portions 28 and 29 joining the upper and lower flat portions. In addition to these parts there are usually introduced the deadening or stiffening bars 30 of wood or other selected materials. Also rod 32 arranged below and extending the full length of said cover 25. While the particular reinforcing elements just described embody the preferred forms for use with this invention, it is not intended in any sense to limit the construction to those forms.

In explanation of the operation of this invention, attention is directed to Figures 2, 3, 4, 5 and 6. The under rails 19 are arranged with suitable tie plates 31 on top of the rails beneath and against the transverse solid portions 16, and the members 1 are placed side by side usually in contact. As illustrated in Figures 3 and 4 the side recesses 14 and 21 of adjoining members come together and form pockets with their upper

surfaces or walls slanting towards the bearing portions 17. The downward pressure or impacts of the traffic all tend to force the ballast or fill against the solid portions 17, and also to hold the ballast in place. It will be noted here that the dished portions 18 also serve to receive and to hold the ballast in place at the ends of the members. It is held to be within the purview of this invention to suitably calk the space between the beads 11 of adjoining members 1 with any selected substance or cement. It is believed to be now clear that I have described a continuous track bed which by reason of the forms of the supporting members 1 may be laid in a straight line or in a curving direction, and that all the surface water will be shed at the ends of the ties, and the ballast held in place against the movement in any direction by reason of the traffic pounding however heavy it may be.

To relieve the stress at centre of tie, and also serve as additional deadening means, clay or the like is interposed between the under-rails 19, so that the ballast surrounds the bottom and sides of the clay filler.

Having now described my invention, and explained the manner of its operation, I claim:—

1. In railway track construction, a track support comprising a plurality of members constructed to be arranged side by side, each member being narrower at one end than at the other end whereby said members may be respectively reversed to form straight track bed and arranged each in the same position with the narrower ends together to form a curved bed, said members being relatively displaceable in a longitudinal direction.

2. In railway track construction, a track support comprising a plurality of members arranged side by side in touch one with another, each of the said members having one narrower end and one wider end whereby a continuous straight or a continuous curved track bed may be formed, said members being relatively displaceable in a longitudinal direction.

3. In a railway track construction, a track support comprising a plurality of members constructed to be arranged side by side, each member being narrower at one end than at the other end whereby either straight or curved portions of the track bed may be formed, and under-rails extending longitudinally and spaced apart beneath the said members.

4. In railway track construction, a track comprising the upper rails, supporting members for the said rails each member having one end narrower and one end wider whereby either straight or curved portions of the track may be formed, and under-rails extending longitudinally beneath the said

members and directly beneath the said track rails.

5. In railway track construction, a track support comprising a plurality of members placed in contact laterally and having flat top surfaces, and recessed under surfaces, each of the said members having one narrower end and one wider end whereby either straight or curved portions of the track may be formed thereby.

6. In railway track construction, a rail supporting member having a middle portion flat and substantially equal in length to the width of the track, said member being adapted to be placed in contact laterally so with an adjacent member and side portions sloping from a middle line in both directions to the ends of the said member.

7. In railway track construction, a rail supporting member having a middle flat portion substantially equal in length to the width of the track, side portions sloping from a middle line in both directions to the ends of the said members, said member being adapted to be placed in contact laterally with an adjacent member and beads formed at the longitudinal edges of the said sloping portions.

8. In railway track construction, a rail supporting member having a middle flat portion substantially equal in length to the width of the track, and side portions sloping transversely downward towards the sides of the said members and sloping downwardly in both directions from a middle line to the ends of the said members, said member being adapted to be placed in contact laterally with an adjacent member.

9. In railway track construction, a rail supporting member having a flat middle portion substantially equal in length to the width of the track, side portions sloping from a middle line in both directions to the sides of the said members and transversely sloping from the said flat portion to the sides of the said members, said member being adapted to be placed in contact laterally with an adjacent member and beads formed longitudinally at the side edges of the said sloping portions.

10. In railway track construction, a rail supporting member having a middle portion flat and substantially equal in length to the width of the track, side portions sloping from a middle line in both directions to the ends of the said member, said member being adapted to be placed in contact laterally with an adjacent member and a plurality of cavities formed in the under side of the said member.

11. In railway track construction, a rail support comprising a member having a middle portion substantially equal in length to the width of the track to carry the track rails, side portions sloping downwardly from

a middle line to the ends of the said member, said member being adapted to be placed in contact laterally with an adjacent member and angular cavities formed in the under side of the said member below the said flat middle portion.

12. In railway track construction, a rail support comprising a member having a middle portion flat and substantially equal in length to the width of the track, said member being adapted to be placed in contact laterally with an adjacent member, side portions sloping downwardly from a middle line to the ends of the member, and reinforcing devices embedded in the said member.

13. In railway track construction, a rail support comprising a member having a middle portion adapted to carry the track rails, said member being adapted to be placed in contact laterally with an adjacent member, side portions sloping transversely and longitudinally with respect to the said middle portion, and reinforcing devices comprising separable and relatively rigid and yielding portions extending lengthwise within the said member.

14. In railway track construction, a rail support comprising a member having a middle portion adapted to carry the track rails, side portions sloping downwardly from a middle line to the ends of the member, and the said member having one narrower end and one wider end and adapted to be placed in contact laterally with an adjacent member.

15. In railway track construction, a rail support comprising a member having a middle portion adapted to carry the track rails, side portions sloping downwardly from a middle line to the ends of the member, the said member having one narrower end and one wider end, and the said member being provided with cavities formed in its under side.

16. In railway track construction, a rail support comprising a member having a middle portion adapted to carry the track rails, side portions sloping from a middle line to the ends of the member, beads formed longitudinally at the side edges of the said sloping portions, and the said member having one narrower end and one wider end and adapted to be placed in contact laterally with an adjacent member.

17. In railway track construction, a rail support comprising a member having a middle portion adapted to carry the track rails, portions extending from a middle line of the member to the ends thereof and arranged at the sides of the said middle portion to conduct water falling thereon away from the said middle portion, and the said member having one narrower end and one wider end and adapted to be placed in contact laterally with an adjacent member.

18. In railway track construction, a rail

support comprising a member having a middle portion adapted to carry the track rails, water shedding portions arranged at the sides of said middle portion, beads extending along the side edges of the said member, and the said member having one narrower end and one wider end and adapted to be placed in contact laterally with an adjacent member.

19. In railway track construction, a rail support comprising a member having a middle portion adapted to carry the track rails, water shedding portions arranged at the sides of said middle portion beads extending along the side edges of the said member, the said member having its vertical side surfaces adjacent to the said beads formed curving.

20. In railway track construction, a rail support comprising a member having a middle portion adapted to carry the track rails, water shedding portions arranged at the sides of said middle portion, the lower portion of the said member being less in width than the combined widths of the said middle portion and side water shedding portions.

21. In railway track construction, a rail support comprising a member having a middle portion adapted to carry the track rails, water shedding portions at the sides of the said middle portion sloping transversely and longitudinally with respect to said middle portion, beads extending along the side edges of the said water shedding portions, and the sides of the said member vertically disposed adjacent to the said beads being of curved form.

22. In railway track construction, a rail support comprising a member having a middle portion adapted to carry the track rails, sloping water shedding portions arranged at the sides of the said middle portion, the vertically disposed sides of the said member being curving in form, and the said member having one narrower end and one wider end.

23. In railway track construction, a rail support comprising a member having a middle portion adapted to carry the track rails, water shedding portions arranged at the sides of the said middle portion and sloping in two directions therefrom, beads extending along the sides of the said member, the vertically disposed side surfaces of the said member being of curving form, and the said member having one narrower and one wider end.

24. In railway track construction, a rail support comprising a member having a middle portion adapted to carry the track rails, water shedding portions arranged at the sides of the said middle portion, the vertically disposed sides of the said member being curved outwardly in form, the lower portion of the said member being less in width than the combined widths of the said middle and water shedding portions.

25. In railway track construction, a rail

support comprising a member having a middle portion adapted to carry the track rails, water shedding portions arranged at the sides of the said middle portion, the vertically disposed sides of the said member being curved outwardly in form, the lower portion of the said member being less in width than the combined widths of the said middle and water shedding portions, and 10 the said member having one narrower and one wider end.

26. In railway track construction, a rail support comprising a member formed of plastic material and having reinforcing devices including side truss rods connected one to another at separated points, and a fabricated mesh wire covering enclosing the said truss rods, the said covering having a flat portion at the top and a flat portion 20 at the bottom and outwardly extending angular portions connecting the said top and bottom portions.

27. In railway track construction, a rail support comprising a member formed of plastic material and having reinforcing devices including side truss rods connected together at separated points, a tubular covering of wire netting enclosing the said truss rods, and stiffening bars arranged lengthwise in the said tubular wire enclosures. 30

28. In railway track construction, a rail support comprising a member having a distinctive cross section near the ends including an upper middle flat portion, water shedding portions sloping downwardly from the said flat portion, vertically disposed curved sides, inwardly inclined portions extending downwardly from the said curved sides, and a lower portion less in width than the combined widths of the said flat portion and water shedding portions. 35

29. In railway track construction, a rail support comprising a member having a distinctive cross section near its ends including an upper middle flat portion, water shedding portions sloping downwardly and outwardly from the said flat portion, beads located at the outer edges of the said sloping portions, vertically disposed outwardly curved sides adjacent to the said beads, inwardly inclined portions extending downwardly from the said curved sides, and a lower portion less in width than the combined widths of the said flat portion and the said sloping portions. 50

30. In railway track construction, a rail support comprising a member having an upper track rail carrying surface, and a lower portion provided with a plurality of cavities, the said cavities being separated by solid portions transversely disposed across the bottom of the member, and longitudinal under-rails arranged beneath the said member in contact with the said solid transverse portions. 60

31. In railway track construction, a rail support comprising a member having an upper track rail carrying surface and a lower portion provided with a plurality of cavities, the said cavities being separated by 70 solid portions transversely disposed across the bottom of the member, longitudinal under rails arranged beneath the said member in contact with the said solid transverse portions, and the said member having one 75 narrower and one wider end.

32. In railway track construction, the combination with longitudinal under rails, of ties extending across and upon the said rails, the said ties having dished cavities in their lower surfaces located between the said rails and the ends of the ties. 80

33. In railway track construction, a rail support comprising a member having dished cavities in its lower surface near its ends, the said cavities being less in width than the maximum width of the end of the said member, and the said member having recesses formed at the sides adjacent to the side walls 85 of the said cavities. 90

34. In railway track construction, a rail support comprising members arranged closely side by side, said members having transverse solid portions located at a distance from the ends of the members, said members having recesses in their lower side edges between said solid portions and the ends of said members the tops of said recesses inclining upwardly towards the said solid portions whereby when two members are together a cavity is formed wherein ballast under traffic pressure is forced towards the said solid portions of the members. 95

35. In railway track construction, a rail support comprising members arranged closely side by side, said members having transverse solid portions located at a distance from the ends of the members, said members having recesses in their lower side edges between the said solid portions and the ends of said members and also between the said solid portions, the tops of the said recesses inclining upwardly towards the said solid portions, whereby when two of the said members are together cavities are formed wherein ballast under traffic pressure is forced towards the said solid portions of the members. 100

36. In railway track construction, a rail support comprising members arranged closely side by side, the said members having a narrower end and a wider end, the said members having transverse solid portions located at a distance from the ends of the members, the said members having recesses in their lower side edges between said solid portions and the ends of the members the tops of the said recesses inclining upwardly towards the said solid portions whereby when two members are together a cavity is 115 120 125 130

formed wherein ballast is forced under traffic pressure towards the said solid portions of the members, and each of the said members having between the said recesses a 5 dished cavity in its under surface near the end of the member.

37. In railway track construction, a rail support comprising members arranged closely side by side and having transverse solid portions spaced from the ends of the members, the said members having cavities in their lower surfaces formed with upper walls inclining upwardly towards the said solid portions whereby ballast under traffic pressure 10 is forced towards the said solid portions of the members.

38. In railway track construction, a rail support comprising members arranged closely side by side and having transverse spaced 20 solid portions joined by longitudinal solid portions, the said members having cavities formed in their lower surfaces with upper walls inclining upwardly towards the said solid portions whereby ballast under traffic pressure 25 is forced towards the said transverse and longitudinal solid portions.

39. In a railway track construction, a track support comprising a plurality of members to be arranged side by side, each 30 of said members having its sides tapered continuously from one end to the other throughout the entire length of the members, whereby said members may be respectively reversed to form a straight track bed and arranged each in the same position with the narrower ends together to form a curved bed.

40. In a railway track construction, a track support comprising a plurality of 40 members arranged side by side in touch, one with another, each of said members having its sides tapered continuously and uninterruptedly from one end to the other throughout the entire length of the member, whereby 45 a continuous straight or a continuous curved, smooth and unbroken track support is formed.

41. In a railway track construction, a

track support comprising a plurality of members having flat top surfaces, recessed 50 under surfaces and uninterrupted sides which taper from one end to the other throughout the entire length of the members, whereby said members when placed in position, contact laterally throughout their 55 entire length, and whereby either straight or curved track portions may be formed.

42. In railway track construction, a rail support comprising a member having dished cavities in its lower surface, and recesses 60 formed at the sides of said member adjacent to the dished cavities.

43. In railway track construction, a rail support comprising members arranged side by side, said members having recesses in 65 their lower side edges, whereby when two members are together a cavity is formed wherein ballast under traffic pressure is forced.

44. In railway track construction, a rail support comprising members arranged side by side, said members having recesses in 70 their lower side edges, whereby when two members are together a cavity is formed 75 wherein ballast under traffic pressure is forced, and each of said members having between the said recesses a dished cavity in its under surface.

45. In railway track construction, a rail support comprising a member having water 80 shedding portions, and an additional water shed separate from but located at and coacting with the ends of said member, whereby the water is deflected entirely away from the bed of the rails and caused to flow downwardly and outwardly at the side of the ballast.

46. In railway track construction, a rail support, and a water shed separate from but located adjacent to and coacting with the 85 ends of said support, whereby the water is caused to flow downwardly and outwardly at the side of the ballast.

In testimony whereof I affix my signature.

GEORGE W. MULLER.
